UNITED STATES PATENT OFFICE.

FRANK A. GRAHAM, OF BUFFALO, NEW YORK.

BOX-MAKING MACHINE.

1,136,795.

Specification of Letters Patent.

Patented Apr. 20, 1915.

Application filed January 4, 1915. Serial No. 428.

To all whom it may concern:

Be it known that I, FRANK A. GRAHAM, a citizen of the United States, residing at Buffalo, in the county of Erie and State of New York, have invented certain new and useful Improvements in Box-Making Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in box making machines and the object in view is to produce a simple and efficient apparatus of this nature so constructed that a blank from which a box is made is trimmed, creased and cut at proper locations where the blank is to be bent to form the sides of the box.

The invention consists of various details of construction, combinations and arrangements of parts which will be hereinafter fully described, shown in the accompanying drawings and then specifically defined in the appended claims.

I illustrate my invention in the accompanying drawings, in which:—

Figure 1 is a top plan view of the apparatus. Fig. 2 is a side elevation. Fig. 3 is a detail view in elevation showing intermeshing gears which operate the cutter rollers. Fig. 4 is a sectional view on line 4—4 of Fig. 1 looking in the direction of the arrows. Fig. 5 is a sectional view on line 5—5 of Fig. 1 looking in the direction of the arrows. Fig. 6 is a detail perspective view of a part of an adjustable guiding member. Fig. 7 is a similar view showing an adjustment of one feature of the invention. Fig. 8 is a detail perspective of a blank having two longitudinal scored lines formed therein by the apparatus. Fig. 9 is a view of the complete blank preparatory to its being folded to box form, Fig. 10 is a view showing the blank folded to form four sides of a box, and Fig. 11 is a detail in elevation of a part of the invention.

Reference now being had to the details of the drawings by numerals, 1 designates the frame of the apparatus having a table 2 forming the top thereof, and 3 designates a driving shaft journaled in suitable bearings

in the frame and upon which a loosely mounted driving wheel 4 is journaled, provided with a clutch collar 5 which is driven by means of the lever 6 into or out of operative relation with the shaft 3, and hand wheels 3^x are fixed to the opposite ends of the shaft 3 for convenience in rotating the same manually if desired for any purpose. Said shaft 3 has keyed thereto a gear wheel 7, shown in Fig. 2 of the drawings, and which meshes with a gear wheel 8 fixed to the shaft 9, which latter is journaled in suitable bearings in the frame.

Shafts 11 and 12 are journaled, the former above the latter, in bearings in the frame, as shown clearly in Fig. 2 of the drawings, and gear wheels 13 and 14 are keyed respectively to the shafts 11 and 12 and intermesh with each other. A transmission gear 14, 75 journaled upon a shaft 15, is in mesh with the two gear wheels 8 and 13 forming means for transmitting motion from one to the other. A beveled gear 16 is keyed to the shaft 12 and is in mesh with a beveled gear 17 mounted upon a shaft 18 journaled in suitable bearings. A gear wheel 20 is fixed to the shaft 18 and meshes with gear wheels (not shown) fixed to the shafts 21 and 22 respectively, which latter are shown in Fig. 85 3 of the drawings. The gear wheels (not shown) which are fixed to the shafts 21 and 22 mesh with shafts 23 and 24, see Fig. 1 of the drawings. At the opposite ends of the shafts 21 and 22 are mounted gear wheels 90 25 and 26 respectively and which intermesh with the wheels 27 and 28 which are fixed to the shafts 29 and 30 respectively, and a gear wheel 31, shown in top plan view Fig. 1 and which is fixed to the shaft 18, meshes with the 95 two gear wheels 25 and 26, as shown plainly in Fig. 3. It will be understood that the arrangement of gear wheels shown in Fig. 3 at the outer ends of the shafts 29 and 30 are similar to the gear wheels before described at the inner end of the shaft. Fixed to the two shafts 30 and 22 are the circular beveled cutting knives 32 and 33 respectively, which are adapted to trim the opposite edges of the blank 34 which is shown in 105 Fig. 1 upon the table of the machine with portions of the blank partially trimmed. Circular-outlined beveled creasing members, designated by numerals 36 and 37, are fixed respectively to the shafts 29 and 21 and 110 serve to form the longitudinal creased lines, designated in the drawings by numeral 38.

The means for guiding the blank 34 after it passes underneath the rollers which receive the longitudinal creases 38 after the opposite sides have been trimmed by the knives described, consists of a bar 39, shown in Fig. 1, adjustably held by means of bolts 40 to the reciprocating plates 41 which have longitudinal movements in the grooves 42 in the table or top of the apparatus. Projecting from the under side of each of said plates 41 is a lug 43 having a link 44 pivoted thereto, which in turn is pivotally connected through the pivot 44^x to the crank arm 45 fixed to the shaft 46, journaled in suitable bearings in the frame. It will be noted that there are two of said links and arms 44 and 45 respectively fixed to the plate 41. A crank arm 47 is fixed to the shaft 46 and has pivotal connection with a pitman 48 which in turn is pivotally connected to the wrist pin 49 secured to a disk 50 fastened to the shaft 3, thus affording means whereby, as the shaft 3 is moved, a reciprocating movement will be imparted to the plates 41 which carry the adjustable feeding bar 39, causing the blank, after it has been scored longitudinally, to feed sidewise toward that part of the apparatus where the transverse cutting lines are scored and slots cut into the opposite edges thereof. As the blank passes between the rollers 29 and 21, it is guided between the adjustable strips 51 and 52, details of portions of which are shown in Figs. 6 and 7 of the drawings, and which are provided with longitudinal slots 54 and 55 through which a bolt 57 passes. Said strips are disposed at an inclination, as shown in Fig. 1, Fig. 7 illustrating more clearly a portion of one of the strips, and a plate 58 is fastened to one of the strips 51 and projects below the lower edge thereof and is adapted to form means for pushing the blank sidewise to receive the transverse scored lines. A guide strip 60, shown in top plan view in Fig. 1, is provided with a longitudinal slot 61, as shown in Fig. 7, and a wedge-shaped block 62 is bolted to one end of the guide strip 51, serving to hold the latter at an inclination, and an angle plate 63 is secured to said wedge-shaped block and has an inverted hook-shaped portion 64 which fits over and is movable upon the upper edge of the strip 60, an adjusting screw 65 passing through the angle plate and also through the slot 61 and upon which a thumb nut 66 is adapted to be fitted to hold the strips 60 and 51 in relatively adjusted positions.

Upon reference to Fig. 6 of the drawings, it will be noted that an angle plate 67 is fastened to a wedge-shaped block 68 and which plate 67 is shown in top plan view in Fig. 1 and serves as a means for separating the strip as it is cut by the circular knives 32, said plate 67 being bolted to the wedge-

shaped member 68 which in turn is fastened to the angle plate 69 through which a screw 70 passes, having a winged nut 71 thereon, said screw 70 passing through the longitudinal slot in a guide strip 72, similar to the guide strip 60 before described. The inner ends of the two strips 60 and 72 are connected to a bar 73 which has a longitudinal dove-tail recess 74 therein, as shown in Figs. 1, 5 and 11 of the drawings. The inner ends of the two strips 60 and 72 have angle plates 75 fixed thereto and a portion of each of said plates 75 is apertured for the reception of a set screw 76, forming means whereby the apertured portion of the plate 75 may be held in a recess in an adjustable block 77, which blocks are similar to the blocks 78 and 79 which carry the adjusting screws 80 upon which the thumb nuts 81 are mounted to hold the blocks in different relative adjustments within the member 73. Each of said blocks 78 and 79 is recessed for the reception of the two members 82 and 83, the former of which is beveled as at 81' at its lower end and serves to hold the blank down against the surface of the table when moved laterally and the other member is forked and has a roller 85 journaled in the ends thereof and serves to frictionally engage the upper surface of the blank as it moves sidewise. The two members 82 and 83 are held in fixed positions in the recesses in which they are mounted through the medium of the screws 86.

Referring to Figs. 1 and 5 of the drawings will be seen segment saws 89 with blank spaces intermediate their ends and upon opposite sides of each segment saw are the disks 90 which are bolted to the saws and underneath each saw are the disks 94 fixed to the shaft E and circumferentially grooved as at 94^x to receive the ends of the teeth of the saw as it rotates in setting the opposite edges of the blank, said disk 94 serving also to support the blank while being cut.

The operation of my invention will be readily understood and is as follows: The blanks from which the boxes are to be made are placed upon the table, as shown in Fig. 1, and fed underneath the two rollers 29 and 30, upon the former of which the beveled scoring disks are mounted and which form the longitudinal scores in the blank. The cutting knives 32 trim the opposite edges, as shown, and the blank as it is fed forward is guided between the strips 51 and 52 which are disposed at an inclination, thus causing the blank to fall down upon the surface of the table. The feeding bar 39 will cause the blank to be fed laterally after the longitudinal scored lines have been formed. As the blank passes underneath the anti-friction rollers 85 and the guiding members 82, it is held down to the table where, as it passes

underneath the scoring members 97, the transverse scored lines will be formed. At each revolution of the shaft 9 carrying the saw teeth, slits will be formed in the opposite edges of the blank in alinement with the longitudinal score lines. Through the medium of the adjusting means, it will be noted that blanks of various sizes may be scored and slits formed for the purpose of making boxes of different sizes.

What I claim to be new is:—

1. A machine for scoring and cutting blanks for paper boxes comprising a frame, rotatable shafts, scoring disks fixed to one of said shafts and cutting knives upon the other shaft and designed to score and trim the edge of a blank, a rotatable saw carrying shaft and saws mounted thereon adapted to slit the opposite edges of the blank, means for feeding the blank in contact with the saw, and means for scoring the blank intermediate the adjacent ends of the slits formed in the opposite edges of the blank.

2. A machine for scoring and cutting blanks for paper boxes comprising a frame, rotatable shafts, scoring disks fixed to one of said shafts and cutting knives upon the other shaft and designed to score and trim the edge of a blank, means for scoring the blank at right angles to the scored lines formed by said disk, a saw carrying shaft, saws mounted thereon and adapted to slit the blank on the opposite edges thereof in alinement with its transverse scored lines.

3. A machine for scoring and cutting blanks for paper boxes comprising a frame, rotatable shafts, scoring disks fixed to one of said shafts and cutting knives upon the other shaft and designed to score and trim the edge of a blank, means for scoring the blank at right angles to the scored lines formed by said disk, a saw carrying shaft, saws mounted thereon and adapted to slit the blank on opposite edges thereof in alinement with its transverse scored lines, disks upon said saw carrying shaft and to which the saws are scored.

4. A machine for scoring and cutting blanks for paper boxes comprising a frame, rotatable shafts, scoring disks fixed to one of said shafts and cutting knives upon the other shaft and designed to score and trim the edge of a blank, means for scoring the blank at right angles to the scored lines formed by said disk, a saw carrying shaft, saws mounted thereon and adapted to slit the blank on the opposite edges thereof in alinement with its transverse scored lines, disks fixed to the saw carrying shaft and secured to the saw, and a circumferentially grooved disk underneath each saw and supporting the blank as the slits are formed therein.

5. A machine for scoring and cutting blanks for paper boxes, comprising a frame,

rotatable shafts, scoring disks fixed to one of said shafts and cutting knives upon the other shaft and designed to score and trim the edge of a blank, adjustable means for receiving and guiding the blank after it has been scored by said disk, means for moving the blank laterally, means for scoring the blank transversely, a rotatable saw carrying shaft, segment saws mounted thereon, saws upon the saw carrying shaft and to which the saws are secured and supporting a circumferentially grooved disk upon each saw upon which the blank rests when being slit, and means for feeding the blank in contact with the saw.

6. A machine for scoring and cutting blanks for paper boxes comprising a frame, rotatable shafts, scoring disks fixed to one of said shafts and cutting knives upon the other shaft and designed to score and trim the edge of a blank, adjustable means for receiving and guiding the blank after it has been scored by said disk, means for scoring the blank transversely, a saw carrying shaft, segment saws mounted thereon, and a circumferentially grooved disk underneath each saw adapted to support the blank while being slit by the saws.

7. A machine for scoring and cutting blanks for paper boxes comprising a frame, rotatable shafts, scoring disks fixed to one of said shafts and cutting knives upon the other shaft and designed to score and trim the edge of a blank, adjustable means for receiving and guiding the means for separating the strip from the edge as it is trimmed from the blank, means for moving the blank laterally, rotatable beveled disks for scoring the blank transversely, a saw carrying shaft and segment saws fixed thereto for slitting the opposite edges of the blank, and a circumferentially grooved rotatable disk underneath the saws and upon which the blank rests while being slit.

8. A machine for scoring and cutting blanks for paper boxes comprising a frame, rotatable shafts, scoring disks fixed to one of said shafts and cutting knives upon the other shaft and designed to score and trim the edge of a blank, adjustable slotted guide bars upon the top of the frame, a thumb screw passing through the slots of the bars and adapted to hold the same in adjusted position and disposed at inclinations to the plane of the top of the machine, reciprocating plates, a bar adjustably connecting the same and adapted to feed the blank laterally, means for scoring the blanks at right angles to the scored lines formed by said disk, a saw carrying shaft, saws mounted thereon and adapted to slit the blank on the opposite edges thereof in alinement with its transverse scored lines.

9. A machine for scoring and cutting blanks for paper boxes, comprising a frame,

rotatable shafts, scoring disks fixed to one of said shafts and cutting knives upon the other shaft and designed to score and trim the edge of a blank, adjustably slotted guide bars upon the top of the frame, a screw passing through registering slots in said bars, a thumb nut upon the screw, a bar having a longitudinal dove-tail groove therein, plates secured to said grooved bar, an anti-friction roller secured to one of said plates, 10 a guide member projecting beyond the edge

of each plate, a strip secured to and projecting at right angles from the bar having said dove-tail groove and secured to said adjustable guide bars. 15

In testimony whereof I hereunto affix my signature in presence of two witnesses.

FRANK A. GRAHAM.
